RECORDING PAPER SYSTEM

John V. L. Hogan, Forest Hills, N. Y., assignor
to Radio Inventions, Inc., New York, N. Y.,
a corporation of New York

Application June 5, 1936, Serial No. 83,618

13 Claims. (Cl. 178—13)

This invention deals with a system and apparatus for keeping and using moist electrolytic recording paper, as in facsimile recording systems for the reproduction of electrically transmitted text and pictures.

More particularly this invention is designed to afford a method whereby a roll of electrolytic recording paper may be kept in the proper condition for use without the necessity of employing 10 special devices to moisten the same just prior to use.

In the art of electrolytic recording it has been found that there is a certain optimum degree of moisture which should be present in paper or 15 other similar material upon which the recording is to take place. Many artifices have been proposed for securing the proper degree of moisture in such a paper.

For example, one method in use has been to 20 pass the paper through a bath containing the electro-sensitive chemicals which are employed to render it ready for use, and then to remove the surplus moisture from the paper and feed it to the marking pen or stylus. Such a system is 25 open to many objections, especially in connection with electrolytic recorders designed for use by the laity. For example, such a system demands apparatus which shall be capable of properly coating the paper. The proper coating of such paper 30 is an operation which demands considerable skill and furthermore the use of chemical baths is undesirable in domestic recorders, because of the liability to spill, the necessity of keeping such a bath at the proper density of solution and the 35 undesirability of having chemicals present in such a form as solutions thereof.

Likewise it has been found in practice very difficult to supply any species of electro-sensitive coating in a form which may readily be applied 40 merely by passing a paper through a bath thereof. Such species of coatings as can be simply applied are not satisfactory from a viewpoint of sensitivity and permanence of marking. The best species of coatings are necessarily applied by persons skilled in the art, since they demand close 45 attention to such factors as the temperature and density of the coating bath, and the speed of the paper passing therethrough. Also many of the better types of coatings require the use of a plurality of baths, rather than a single bath. Likewise the removal of the surplus solution from such papers is also very difficult to secure by means of simple apparatus which may readily be incorporated in a domestic receiver.

55 An alternative system which has been proposed,

is to impregnate the paper with the required chemicals and then allow the paper to dry substantially entirely. The paper is then passed through a water bath just prior to using. This system has several disadvantages. The water 5 bath tends to remove some of the active chemicals from the paper as it passes therethrough, until such bath has reached a very high degree of concentration with respect to the soluble chemicals employed. Under such conditions, the bath 10 eventually becomes a chemical solution, thus giving rise to the disadvantages previously pointed out in connection with the first described system. Likewise the same problems with respect to removing the surplus moisture, are present 15 with this system.

I have found that the most efficient method of manufacturing, shipping and utilizing electrolytic recording paper in domestic apparatus, is to properly coat and sensitize the paper, as well 20 as to bring it to the proper degree of moisture, at the place where the paper is packed for shipment. In this way, very sensitive and permanent types of chemicals may be employed to render 25 the paper sensitive, and the surface of the paper may be finished so that it will cooperate with the marking stylus to give the best results.

I have found that by the employment of suitable coating or impregnating mixtures, a paper 30 may be produced which will function efficiently over a considerable range of moisture content. Accordingly if such a paper is produced with the maximum allowable degree of moisture therein, is shipped in sealed containers so that the evaporation during transit is reduced to a minimum 35 and if the domestic recording device is supplied with a suitable type of container and with other suitable means for substantially preventing the evaporation of moisture while the roll of paper is in the machine and also while the paper is 40 passing from the container to the point of marking, it is possible to completely avoid the necessity of using any kind of chemical or water bath in connection with the recorder. Moreover, the 45 operation of the recorder is improved and stabilized, for the paper is presented to the marking point with substantially the optimum moisture content, and regardless of whether the recorder is being operated in a dry or a humid atmosphere.

The amount of humidity in the atmosphere 50 varies greatly and may extend from a low degree which is far below the degree required in a facsimile paper for optimum results, to a degree greater than that desired. If a paper be exposed for a relatively long time to the atmos- 55

phere, as is the case in that type of recorder which uses a sheet wrapped about a drum, it will be only at very rare times that such sheet will be exposed to an atmosphere which will maintain its moisture content at the proper degree. If too moist, there will be difficulty in obtaining sharp definition or with the marking stylus digging into the paper, and if too dry, the marking will be faint and unsatisfactory.

10 Previously one practice has been to have the paper more moist than desired and depend upon the atmospheric evaporation to reduce the moisture to the desired degree, but in view of the widely varying degree of moisture in the atmosphere such procedure has been most unreliable and very unsatisfactory. I have found that more than about fifteen seconds to one minute of exposure to the open air is dangerous and accordingly I prefer to so shield my paper and so to feed it, that the maximum time of exposure to the air shall not substantially exceed such a period of time.

With respect to the processes above described where the paper is moistened just prior to marking thereupon, great difficulty is experienced in apparatus designed for domestic use, in drying such paper to the proper degree before passing it beneath the marking stylus, all of which difficulty is avoided by the employment of the process of my invention.

25 The construction and operation of my invention will be more clearly explained by reference to the accompanying drawing, where one form thereof is shown.

30 Fig. 1 is an end elevation in cross section upon the line I—I of Fig. 2.

35 Fig. 2 is a side elevation partly in cross section and with certain portions cut away.

40 Fig. 3 is a detail showing the connection of an electrical switch with the sliding shield shown in Fig. 1.

45 In the drawing, the members 10, 10 represent portions of the frame of the recorder. A substantially closed container 11 is held in this frame and located properly with respect thereto by means of a pin 12 which engages a slot 13 in frame 10. Additional supports 14, 14' may also be used to aid in holding the container 11 in place. Within this container is a spool 15 upon which is wound the paper 16. Spool 15 is provided at its end with flanges 17 and the central point of these flanges may be supplied at either end with an opening 17' fitting upon a projecting pin 18' supplied with an enlargement 19' serving as an axis of rotation, by passing through the opening 17', and may be supplied at either end with a frictional spring device 19 which serves to prevent spool 15 from rotating, except when a force indicated by the arrow 20 is applied to the portion of the paper strip 21, which has passed beyond the marking stylus 22.

50 However, it is to be understood that a rotative force may be applied to spool 15 by any other suitable means. For example paper 16 may have a pulling force applied thereto at some point prior to its passage under the marking stylus 22, provided the paper is also properly drawn over the platen 25. The portion of the paper strip 23, just after leaving the parent roll of paper 16, passes through a long slit-like opening 24 which runs longitudinally of container 11. This slit is preferably made no wider than is necessary to allow the paper to pass therethrough

5 without undue friction. In case that container 11 is constructed of some material which would be deleteriously effected by the chemicals employed in the paper, the edges of slit 24 may be lined with some material not acted upon by the chemicals, such as phenolic insulating resin. Just adjacent one side of slit 24 lies the marking platen 25, which may be held in frame 10 by pins such as shown at 18 and is placed closely adjacent container 11 so as to minimize any considerable circulation of air between the two.

10 On the other side of the slit is located a guard member 26 which extends around a portion of the periphery of platen 25 with sufficient space therebetween for paper strip 23 to pass between the two members on its way to stylus 22. This guard 26 I have found to be of great importance in preventing the partial or complete drying out of the paper while in passage between slits 24 and stylus 22. Likewise another guard (not shown) may be placed between the platen 25 and the container 11 to reduce the evaporation through any space between these elements. Such guard may rest lightly upon platen 25, so as not substantially to retard the rotation of the latter.

15 The atmosphere within container 11 soon reaches a condition of equilibrium with respect to its moisture content and that of paper roll 16, and therefore evaporation within container 11 is minimized. As stated, I find it desirable to employ a shield 26 further to prevent evaporation from the paper after it leaves container 11, and so to avoid the drying action which will take place while the paper moves from the container to the marking point, if the atmosphere is relatively dry.

20 In order to facilitate the threading of paper strip 23 through slit 24 I have found it convenient to make container 11 of some material of an elastic nature, such as metal sheet, and so to bias this strip that it will, when allowed so to do, expand in a fashion tending to widen slit 24. I then provide a rigid end cover 27, having therein grooves 28 for the reception of the ends of cylindrical 45 container 11. Accordingly when cover 27 is removed for the purpose of inserting a roll of paper into container 11, the elasticity of the walls of container 11 will cause them to expand so that slit 24 has an average width considerably greater 50 than normal, thus allowing the paper readily to be threaded therethrough. Then when cap 27 is replaced upon the end of container 11, it will be necessary to squeeze together the walls of container 11, in order for its end to seat itself in 55 grooves 28, thus automatically restoring the correct width of slit 24.

25 Referring now to the device incorporated in my invention for still further reducing the leakage of moisture through slit 24, I have found it desirable to utilize a movable cover which will substantially completely close this slit, and which will only open the same when the recorder is in operation. One convenient way of accomplishing this result automatically, is to use a suitable form 65 of electrical switch 30 for setting in motion the recorder, and to couple this switch with such a closure device as that just mentioned. For example, the switch 30 may be of the type known as a toggle switch, having a lever 31 and a manipulating handle 32. Lever 31 will move vertically from the position shown in Fig. 3 by unbroken lines to the alternative position shown by dotted lines. This lever 31 is connected by a rigid mechanical link 33 to a short rigid projecting piece 75

34 which extends through shield 26 and terminates in a shielding cover 35 which is formed as a portion of a cylinder having its internal radius substantially equal to the external radius of cylindrical container 11.

5 In Fig. 1, the shielding cover 35 is shown pulled downwardly to its lower position, at which point its upper edge lies below slit 24, thus allowing paper strip 23 to pass through the slit without 10 encountering shield 35. When switch 30 has its handle 32 thrown upwardly, as shown in Fig. 3, then shielding cover 35 will also be pushed upwardly, taking with it a small length of the paper strip 23, which portion of paper is thus squeezed 15 between cover 35 and container 11 and affords a substantially hermetic seal for the container.

It will thus be seen that the same operation which determines the discontinuance of recording, will effectuate the sealing of the paper roll against 20 evaporation of its moisture and conversely when the recorder is put into operation, by snapping down handle 31, container 11 will be opened sufficiently to allow paper 16 to pass outwardly therefrom. It is true that the portion of paper strip 25 23 lying between slit 24 and stylus 22 will not be so efficiently protected during periods when the recorder is not in operation. However, the length of paper thus involved is very small and it is a simple operation when setting the recorder into 30 operation, to feed forward strip 23 until a moist portion thereof lies beneath stylus 22.

35 I have found it convenient in the manufacture of the rolls of electro-sensitive paper, to cover the outermost layer of such paper with a strip of some material substantially impervious to moisture, such as paraffin paper. This strip will fit snugly between the two end flanges of the spool of paper and thus will afford a still further moisture-retaining seal for the spool while it is being transferred from the shipping container to the recorder paper-containing receptacle 11. Furthermore I have found it advantageous to attach such a dry covering strip at one of its edges to the electro-sensitive paper proper, thus allowing this 45 dry strip to be fed conveniently through slit 24 when the spool is inserted in the receptacle, and to act as a "leader" for the sensitive paper.

50 Many advantages of my invention will be apparent to those skilled in the art, but it is particularly to be noted that my invention simplifies and stabilizes the use of moist electrolytic recording papers to such an extent that it is feasible for the laity to employ such papers in domestic use, which has hitherto been considered 55 commercially impossible. By the use of a paper which is brought to its proper degree of moisture by those skilled in the art at the point of manufacture, and which then is kept from losing such moisture (or from absorbing excess moisture) until 60 after the record has been made thereupon, I secure great practical and economic advantages.

65 While I have described one form of my invention, it is to be understood that this form is given only as an example of the application of my invention and that my invention is limited only by the scope of the hereunto appended claims.

I claim:

70 1. A method of manufacturing, transporting, storing and using moisture-containing electrolytic recording paper, including the steps of producing said paper with substantially the optimum degree of moisture present therein, transporting said paper while substantially preventing the evaporation of moisture therefrom, storing said paper 75 closely adjacent to the point of marking, while

substantially preventing evaporation of moisture from said paper, passing said paper through a channel closed away from free access of air currents thereto, so as to retard evaporation from said paper while passing through said channel, 5 and exposing said paper to the air only as required for marking purposes and only when substantially at the point of marking.

2. Apparatus for transporting, storing and using electrolytic recording paper, including 10 means for sealing said paper from exposure to the air during transportation, substantially closed means for storing said paper adjacent to the recording point, means for withdrawing the paper from said storage means, at a rate 15 proportional to the speed of recording and only when recording thereupon, means for actuating said withdrawal means and evaporation reducing means substantially completely shielding said paper during transit between said storage 20 means and said recording point.

3. Apparatus according to claim 2, and also including means for substantially sealing the closure of said storage means, when said paper is not being withdrawn therefrom, said sealing 25 means substantially entirely preventing movement of said paper therethrough when closing said storage means and exerting substantially no frictional restraint upon the movement of said paper therethrough after opening said storage means. 30

4. Apparatus according to claim 2, characterized in that the storage means has means for altering its degree of closure, and means for coupling said altering means with said paper withdrawal actuating means, whereby the actuation of 35 the withdrawal means will simultaneously render the degree of closure a minimum and vice versa.

5. Apparatus according to claim 2, characterized in that the means for withdrawing the paper is electrically driven, the actuating means is a 40 switch having a reciprocating handle, and also including means for substantially completely sealing and unsealing the closure of said storage means, and connecting means between said switch handle and said sealing means whereby the actuation of said withdrawal means will at the same time cause the unsealing of said storage means. 45

6. An electrolytic paper recording system including a substantially closed container storing pre-moistened paper, a mechanical feeding device 50 withdrawing paper from said container when said recorder is in operation and a substantially closed passageway extending from the point of withdrawal of said paper to the point of recording thereupon. 55

7. A recording paper system including a substantially closed receptacle containing pre-moistened paper, a feeding device withdrawing paper from said container, a platen over which said paper passes and means for marking upon 60 said paper while passing over said platen, said platen and said receptacle being placed closely together, whereby said platen acts to shield one side of said paper from atmospheric action while said paper passes from said receptacle to the 65 marking position on said platen.

8. A facsimile paper supply and recording system including means for storing recording paper, means for substantially preventing drying of said paper during storage comprising a substantially 70 moistureproof flexible sheet closely surrounding and in close contact with said recording paper and a further moistureproof container surrounding said flexible sheet and said paper, means for minimizing drying of said paper when in use 75

- comprising a substantially closed container therefor, having a narrow open slit for the withdrawal of paper therefrom, means for reducing drying of said paper while in transit between said slit and the point of recording comprising two moisture-proof surfaces adjacent to one another and providing therebetween a passageway for said paper, and means for impelling said paper from said closed container through said slit and said passageway to said point of recording.
9. A recording system according to claim 8 and also including means for substantially completely closing said slit when paper is not passing through, whereby movement of paper through said slit is mechanically restrained when said slit is closed.
10. A recording system according to claim 8 further characterized in that it includes means for setting in motion the paper impelling means, means for closing the paper slit and means connecting said last two means whereby the setting in motion of the paper impelling means will open the slit and the stoppage of the paper impelling means will close the slit.
11. An elongated hollow fascimile paper container provided with a longitudinal slit and including a removable cap at one end, said slit extending to the end at which said cap is located and said container being formed of material having a tendency to return at least partly to a flat sheet, whereby the removal of said cap will cause said slit to become, at least in part, wider, so as to facilitate the insertion therethrough of a paper strip.

12. The process of electrolytic recording upon paper including the steps of storing the paper at a point adjacent to the marking point and at the proper degree of moisture, withdrawing the paper at a rate proportional to its use, protecting it from evaporation after withdrawal and presenting it to the marking point containing a degree of moisture substantially equal to that present in said paper during storage.

13. A paper storing and feeding device for electrolytic paper recorders of the type described including means for storing the paper in equilibrium with an atmosphere containing a predetermined optimum degree of moisture, means for withdrawing said paper only when recording thereupon is practiced and at a rate no greater than the rate at which said recording is practiced, and means for maintaining a substantially undiminished degree of moisture in said paper while passing between said storage means and the point where said recording is practiced thereupon, said last mentioned means including a passageway extending for substantially the entire distance between said storage means and said recording point, said passageway being closed away from free access of air currents thereunto, whereby evaporation of moisture from said paper, while in transit through said passageway, is very materially diminished.

JOHN V. L. HOGAN. 30
